United States Patent Office.

WILLIAM E. HOPKINS, OF PARKMAN, OHIO.

Letters Patent No. 72,640, dated December 24, 1867.

IMPROVEMENT IN STAVE-MACHINES.

The Schedule referred to in these Letters Patent and making part of the same.

TO ALL WHOM IT MAY CONCERN:

Be it known that I, WILLIAM E. HOPKINS, of Parkman, Geauga county, State of Ohio, have invented a Stave, Heading, and Shingle-Machine; and I do hereby declare the following to be a full, clear, and exact description of the same, reference being had to the accompanying drawings, in which—

Figure 1 is a plan or top view of a stave, heading, and shingle-machine constructed in accordance with my invention.

Figure 2 is an end elevation, and

Figure 3 is a front elevation of the same.

Figure 4 is a plan view of the adjustable saw-table, and

Figure 5 is an end view of the same.

Similar letters of reference denote corresponding parts in all the figures.

My invention consists in the employment of a narrow endless belt-saw, arranged to work upon pulleys or wheels, in connection with an adjustable feed or saw-table, in such manner as to adapt the one saw to sawing of staves for casks or vessels of different diameters or dimensions, and also to the sawing of shingles and headings, as will be hereinafter described.

In the accompanying drawings, A represents a framing of any suitable construction, and of the required dimensions to adapt it to the work it is to perform. Said framing consists, in this instance, of four corner uprights or posts, A, connected together at the top and bottom by horizontal frame-pieces, A¹, the whole forming a stout table or bench of the desired height, and provided with suitable boxes or bearings, in which are mounted the two upright shafts B B', to one of which, B, motion is communicated in any suitable manner. The shafts B are arranged at the opposite sides or ends of the framing, and are armed on their upper ends with the large flanged pulleys of wheels C C', upon which is mounted the endless saw-belt D, to which motion is imparted from one of the pulleys C, and which, in turn, communicates motion to the pulley or wheel C'. The bearings of shaft B' are made adjustable, to and from the bearings of shaft B, to admit of the ready application and removal of the saw-belt when desired, and also for the purpose of giving the proper tension to said belt. The adjustment of the bearing is effected, in this instance, by means of set-screws b b. Any other suitable device for the purpose may be used. The flange e, formed upon the side of the wheel C, serves to maintain the belt-saw upon the pulleys in its proper working relation, and to prevent its being thrown off, by the pressure against it, of the block from which the staves are being cut or sawed.

The frame A is shown as extended upon its opposite sides in front and in rear, (see figs. 1 and 2,) to form suitable supports for the adjustable saw-tables E and F, the supports for the table E consisting of an extension of the frame-pieces A¹ of the main frame, or pieces attached thereto, and provided with adjustable boxes or bearings, in which the saw-table is pivoted, as shown at e. The saw-table E (represented in plan and end views, figs. 4 and 5) may be of any desired construction, and is mounted on pivotal supports, e' e'. These pivots, e', are made adjustable, relative to the table and its supports, in such manner as to vary the distance of the pivots upon which it turns, or its fulcrum, from the saw, in connection with which it is operated. The object of this adjustment will be apparent, viz: the distance of the fulcrum or table is fixed at a distance corresponding to the radius of a circle, in an arc of which it is desired to cut the staves; in other words, in the arc of a circle whose diameter conforms to the diameter of the cask or vessel for which staves are to be cut. It will also be seen that, by arranging the opposite pivots out of line with each other, thereby giving to them the diagonal relation shown in fig. 4, the movement described by the forward or saw-edge of the table will be in the path of arcs of circles of different diameters, varying according to the varying distance of the pivotal points in the table from the saw or face of the table adjacent to the saw. E¹ are clamping-levers, pivoted to the saw-table, and armed on their inner ends with "dogs," for seizing and holding the blocks or pieces to be sawed. E² is a locking-lever, for locking or clamping the levers after they have properly grasped the block to be sawed. G is a set-board or gauge, for regulating the thickness of the staves, and which may be made adjustable by means of slots and set-screws, or in any other usual or convenient manner. G' is a guide-block, for steadyng and guiding the thin belt-saw in entering the block to be sawed. Upon the opposite side of the table or frame A

to saw-table E is another saw-table, F, adapted to the sawing of headings for kegs, barrels, &c. In this instance, the table is arranged to move vertically in grooved guide-ways or uprights, A² A², attached to the frame A.

The sliding saw-table F is provided with clamping-levers and set-board or gauge, similar to those on table E, and for a similar purpose, the gauge or set-board G, in this instance, also being made adjustable, for varying the thickness of the heading or shingles, as required. The saw-tables are maintained in proper position to receive the blocks to be cut by means of springs of any suitable construction, and applied in any convenient manner, or by means of counterpoise weights, as may be preferred. In this instance, I have shown rubber springs, f f, attached at one end to the saw-table, and at the other end to the table-supports or frame A.

The saw should be made of a thin and narrow plate of steel, so as to possess the functions of a driving-belt, and be free to turn readily in the direction of its width in the block operated upon, for the purpose of giving the desired curvature to the staves cut therefrom; and, at the same time, it must be sufficiently elastic or pliable to conform to the faces of the pulley around which it passes. While between the points of contact with the opposite pulleys, by the tension exerted thereon by the pulleys when properly adjusted, it is drawn into right lines, of sufficient length to accommodate the greatest length of staves to be cut.

The saw has been described and shown as arranged vertically, in the direction of its width, upon horizontal pulleys, or pulleys mounted on vertical shafts; but it will be apparent that shafts may be arranged horizontally, if preferred, and a vertical position given to the saw-tables conforming thereto. The saw, in this case, may be extended in length, so as to accommodate more than one saw-table. The pulleys or wheels may be enlarged, to permit the arrangement of the tables one over the other, or the belt-wheels may be arranged one over the other on horizontal shafts, and the table side by side, if preferred. The surface of the pulleys may be slightly roughened, if desired, to prevent the slipping of the belt.

It will be seen that the staves are sawed lengthwise in a right line, that any desired curvature in the direction of their width is given by the adjustment of the fulcrum or pivotal point of the saw-table, in the manner explained, and also that, by a diagonal arrangement of the pivot or fulcrum, or an arrangement thereof more or less approaching a diagonal, the staves may be cut of a form suitable for tubs or vessels of a greater diameter at one end than at the other.

The machine is readily adapted to saw staves of different lengths, by simply adjusting the clamping-levers, so as to properly hold the block to be sawed. One of the clamping-levers, or arm and dog, (that which resists action of the saw upon the block,) may be rigidly attached to the saw-table, or both may be made adjustable, as preferred.

It will be obvious that other means than those shown and described for adjusting the saw-tables may be used; but these sufficiently illustrate the nature and object of my invention, viz, the provision of means whereby staves for casks and vessels of different diameters may be cut or sawed by the same machine.

What I claim, and desire to secure by Letters Patent, is—

The adjustable feed or saw-table, for regulating the degree of curvature of the staves to conform to the diameter of the cask or vessel for which they are to be used, in combination with the narrow endless-belt saw, arranged and operating as described.

W. E. HOPKINS.
